UNITED STATES PATENT OFFICE.

ERIC HEDBURG, OF JOPLIN, MISSOURI, ASSIGNOR, BY MESNE ASSIGNMENTS, TO AMERICAN REDUCTION COMPANY, OF CHICAGO, ILLINOIS, A CORPORATION OF ARIZONA TERRITORY.

ORE-SLIME SEPARATOR.

No. 804,841.

Specification of Letters Patent.

Patented Nov. 21, 1905.

Application filed August 8, 1904. Serial No. 219,888.

To all whom it may concern:

Be it known that I, ERIC HEDBURG, a citizen of the United States, residing at Joplin, Missouri, have invented certain new and useful Improvements in Ore-Slime Separators, of which the following, taken in connection with the drawings, is a specification.

My invention has for its object the production of an ore-slime separator by means of which the finer concentrates, which collect on top of the water, are not carried along and passed out with the current, as has been the case with apparatus of this kind heretofore used, but are collected and saved and caused to settle in the ore-bed with the coarser ores.

I have illustrated my invention in preferred form in the accompanying drawings, in which—

Figure 1 is a longitudinal sectional view of my invention. Fig. 2 is a cross-sectional view of the same. Fig. 3 is a perspective detail of one of the partitions.

In carrying out the invention I have constructed the jig with the usual ore-beds A, each being provided with a hutch B and being separated by partitions b. Any number of compartments desired may be provided, usually from five to seven. The bottoms of the ore-beds are covered with a fine screen or sieve, through which the fine metal drops by gravity. The ore is fed into the jig at C and settles into the different compartments, the fine minerals settling into the hutches B. Water is supplied to the jig through the trough C from any suitable source of supply and is kept constantly flowing over the ore-beds A and passes from the jig through the spout D. When in operation, the ore-beds are kept agitated by the operation of the jigs E, which are connected to and operated by the eccentrics E', which are mounted upon a shaft driven by any suitable source of power.

In ore-jigs as heretofore constructed it has been impossible to save the fine ore-slimes which float upon the surface of the water and are carried off with it, as it passes over the sieves and is lost with the overflow.

As shown in the drawings, I have provided an ore-separator having a plurality of compartments separated by partitions b, said partitions being of different heights, as shown in Fig. 1, thus permitting the ore passing over

one partition to gravitate into the ore-bed A of the next partition, and so on through the different compartments. The ore bed or screen in the first compartment at the receiving end C of the jig is placed near the top of the first partition b, and the screens in each of the succeeding compartments are placed slightly lower than the one preceding it. It will thus be seen that the tops of the partitions b and the ore-beds are arranged on an angle from the receiving end C to the discharge D of the jig.

In the frame of the jig I have provided vertical grooves e. F represents partitions or deflectors which are provided at each end thereof with a spring f. These deflectors F are made of a size adapted to slide in the vertical grooves e in the jig-frame and are held in position by the pressure of the springs f.

In operation the partitions or deflectors are adjusted to position in the grooves and are extended below the surface of the water, as shown. The fine ore which floats upon the surface of the water will pass over the top of the partitions b until it comes in contact with the first deflector F, which will throw it into the suction of the ore-bed of the next compartment, where it will settle and pass through the screen in the ore-bed of that compartment. Any of the finer suspended particles of ore which might be drawn by the current of water over the partition b will come in contact with the second deflector and be thrown into the suction of the ore-bed of the next compartment and there settle to the bottom, and so on until all of the fine ores have been preserved. For ordinary use I have found it desirable to use two or three of these deflectors in the jig; but it is obvious that any number might be used as found desirable in order to deflect all of the finer particles of ore which otherwise are carried upon the surface of the water and lost in the overflow.

It will thus be observed that I have provided a simple and effective arrangement for securing and preserving all the fine metals in the ore. I do not desire to limit myself to the construction shown in the drawings, as the details thereof may be changed without departing from the spirit of my invention, which consists, essentially, in providing means for arresting and settling the ore-slimes floating with the current of water passing over the ore-beds.

Obviously the partitions or deflectors need not be of the number, shape, or size which I have shown and need not have the spring arrangement for holding in place and need not be disposed therein in grooves, as I have shown; but any other manner of disposing these partitions or deflectors so as to create a still surface in the water passing through the jig and allow the ore-slimes to settle and be passed into the hatches I should contemplate as coming within the spirit of my invention.

I claim—

1. An ore-separator provided with a plurality of sections, a hutch at the bottom of each section, a screen covering said hutch, a plunger-compartment and plunger therein, adjustable partitions between the sections adapted to form passages in close proximity to the ore-beds and adapted to deflect the finer ores into the uplifted beds whereby the finer ores may work through the screens into the hatches, substantially as described.

2. An ore-separator provided with a plurality of sections, a plunger-compartment in each section and a plunger therein, a hutch at the bottom of each section a screen ore-bed near the top of each of said hatches, adjustable de-

flectors or partitions between the sections, the walls of said sections having grooves in which said partitions may slide, said partitions adapted to form passages in close proximity to the ore-beds and to deflect the finer ores into the ore-beds, whereby said finer ores may work through the screens into the hatches, substantially as described.

3. In combination with a plunger-jig, a plurality of jig-sections having ore-beds located at different heights between said sections, hatches beneath said ore-beds, adjustable partitions having springs upon the ends thereof, the walls of said sections having grooves into which said partitions may slide, said partitions adapted to form passages in close proximity to the ore-beds, and to deflect the finer ores into the ore-beds, whereby said finer ores may work through said screens into the hatches, substantially as described.

In testimony whereof I have hereunto signed this specification in the presence of two subscribing witnesses.

ERIC HEDBURG.
